UNITED STATES PATENT OFFICE.

RALPH V. SAGE, OF COLUMBUS, OHIO.

STIFFENING MEMBER FOR CAR SIDES.

1,214,080.

Specification of Letters Patent. Patented Jan. 30, 1917.

Application filed May 1, 1914. Serial No. 335,594.

To all whom it may concern:

Be it known that I, RALPH V. SAGE, a citizen of the United States, residing in the city of Columbus, in the county of Franklin and State of Ohio, have invented certain new and useful Improvements in Stiffening Members for Car Sides; and I do hereby declare the following to be a full, clear, and exact description of the invention, such as will enable others skilled in the art to which it appertains to make and use the same.

My invention relates to stiffening members for cars, such as the side stakes, end braces, side members, etc., and my object is to produce the same by a cheap and simple method whereby the distribution of the metal in cross-section is economical, practical and well adapted to produce the results desired.

When trough-shaped stakes or end braces are used in car construction, I find it desirable to thicken the apex portion in order to increase the strength and rigidity at this point of greatest stress.

To this end my invention consists generally in making car stiffening members of trough-shape having a thickened apex portion and integral outwardly extending flanges along their side edges, by first rolling a substantially flat or rounded V shaped plate or bar with a centrally thickened portion extending longitudinally thereof, then cutting the bar or plate into the desired lengths, and then shaping these lengths between forming dies to complete the operation.

Having thus given this general description of my invention, I will now, in order to make the same more clear, refer to the accompanying one sheet of drawings forming part of this specification and in which similar characters of reference designate like parts.

Figure 1 illustrates the end portion of a car body in side elevation showing the manner of attaching the stakes or end braces to the car. Fig. 2 is a car stake with thickened apex and of uniform cross section throughout its length. Fig. 3 is a transverse section of a rolled plate having a thickened central portion extending above the upper face of the plate and showing in dotted lines the outline of the stiffening member after it is finally formed. Fig. 4 is a transverse section of a rolled plate having a thickened central portion extending from the lower face of the plate and showing in dotted

lines the outline of the stiffening member after it is finally formed. Fig. 5 is a transverse section showing a car stake attached to the car side taken on the line V—V of Fig. 1. Fig. 6 illustrates the manner of rolling the plate from which the stiffeners are made, showing the finishing pass in the rolls. Fig. 7 illustrates in cross-section the dies employed in pressing the plate or bar of metal so as to form my improved stiffeners, this view showing a plate of metal formed into shape between the dies. Fig. 8 is a side elevation of an end brace having a straight attaching flanged face. Fig. 9 shows in side elevation an offset end portion of one of the end braces adapted to fit over a corresponding projection on the car. Fig. 10 illustrates in front and side elevations another form of car stake having a tapered trough-shaped rib running longitudinally thereof, this form being well adapted to act as a cantaliver in use. Fig. 11 illustrates another manner of rolling a plate into substantially V shape, with rounded apex instead of flat as shown in Figs. 3 and 4, thus saving work in the final die forming operation.

Referring to the drawings in detail, the numerals 1 and 2 indicate rolls for forming my improved plate, at least one of said rolls having an annular groove 3 concaved centrally as at 4 to form the finishing pass through which the bar 5 is passed, the concaved portion 4 of the pass forming on the bar as it passes between the rolls a thickened or convex portion as at 6. In this manner a flat bar or plate is formed, thickened or convexed centrally on the face of the plate throughout the entire length thereof. The finished bar is then cut into the desired lengths and pressed between forming dies 7 and 8, the upper die 7 being the male having the rounded projection 9; and 8 is the female die having a trough-shaped depression 10.

In forming car stakes or the like, the male die is raised so that the plate which has been rolled of forms shown in Fig. 3, 4 or 11 is inserted between the dies; the dies are then pressed together and assume the position illustrated in Fig. 7 thus forming a stake or brace of trough-shape with inclined sides 11, flanged edges 12, and a thickened apex portion 13.

The stakes are attached to the car sides by means of rivets 15 as indicated in Figs.

1 and 5. These stakes may be constructed in various forms as illustrated and indicated by the numeral 17 in Fig. 1, with an outwardly extending flange at the top and the lower part of the rib tapered; or as 18 in Fig. 10, with the rib tapered from an intermediate portion of the stake toward each end, or as 19 in Fig. 2 where the rib is of uniform section throughout its length. 10 The end braces or other stiffeners may also be made in slightly modified forms as indicated at 20 in Fig. 1 where the brace is of uniform section throughout its length; or as 21 in Fig. 8 where the rib tapers from 15 the center of the brace toward each end with a straight flanged attaching face; or the ends of the brace 22 may be offset as at 23 in Fig. 9 to fit over a corresponding projection on the car. 20 In Fig. 11 I have illustrated another form of a finished bar 16 which is substantially V shaped in cross-section with a rounded apex. These forms of stiffeners which are of uniform section throughout their length 25 may be formed either by passing the bar between rolls, or by pressing as illustrated in Fig. 7.

Although I have shown and described my invention in considerable detail, I do not 30 wish to be limited to the exact construction specified, but may use such substitutions, modifications or equivalents thereof, as are

embraced within the scope of my invention, as pointed out in the claims.

Having thus described my invention, what I claim and desire to secure by Letters Patents is:—

1. A stiffener for a car wall, comprising a tapered trough-shaped member provided with outwardly extending free edges, and a thickened integral apex portion. 40

2. A stiffener for car walls, comprising a tapered trough-shaped member provided with an integrally thickened apex portion. 45

3. A stiffener for car walls, comprising a trough-shaped member having its greatest height intermediate of its ends and gradually decreasing therefrom, said trough-shaped member being provided with outwardly extending flanges, and a thickened 50 integral apex portion.

4. A stiffener for a car wall, comprising a trough-shaped member gradually decreasing in height from an intermediate part toward its ends, said trough-shaped member being provided with a thickened integral apex portion, and a flange extending entirely around its edges. 55

In testimony whereof I hereto affix my signature in the presence of two witnesses. 60

RALPH V. SAGE.
